(57) **CLAIM**

I claim the ornamental design for a sternum saw blade, as shown and described.

DESCRIPTION

FIG. 1 is a side plan view of a sternum saw blade with notches;

FIG. 2 is a bottom plan view of the sternum saw blade with notches;

FIG. 3 is a top plan view of the sternum saw blade with notches;

FIG. 4 is a front plan view of the sternum saw blade with notches;

FIG. 5 is a rear plan view of the sternum saw blade with notches; and,

FIG. 6 is a top elevational view of the sternum saw blade with notches.

The broken line showing is for illustrative purposes only and forms no part of the claimed invention.
